SURGICAL INSTRUMENT

Simon H. Sauter, Highland Park, Mich.

Application February 11, 1942, Serial No. 430,379

11 Claims. (Cl. 128—340)

This invention relates to surgical instruments and in particular to hemostats.

One object of this invention is to provide a hemostat having a quickly attachable and detachable surgical needle in combination therewith, so that a suture may be easily and quickly inserted in the tissue after the latter has been clamped to halt bleeding.

Another object is to provide a hemostat as set forth in the preceding object wherein the needle is positively guided relatively to the clamping jaws of the hemostat so that it will always enter a part of the tissue located in a definite and accurate position relatively to the clamping jaws.

Another object is to provide a hemostat equipped with a quickly detachable surgical needle and suture holder such that the hemostat may first be applied to the tissue to stop the bleeding, and shifted to another position if the bleeding does not stop immediately, after which the needle may be attached and caused to be guided accurately into the tissue by the device without danger of its passing through the wrong part of the tissue, thereby always drawing the suture through the proper part of the tissue without the necessity of guidance on the part of the operator after the hemostat has once been successfully clamped.

Another object is to provide a hemostat having a surgical needle attachably and detachably combined therewith in such a manner that the needle may be instantly attached and detached merely by turning a small knob.

Another object is to provide a hemostat combined with an attachable and detachable surgical needle wherein the needle is accurately pivoted around the pivot axis or the hemostat jaws and caused to pass accurately through apertures or notches in the ends of the hemostat jaws.

Another object is to provide a hemostat combined with an attachable and detachable surgical needle such that a series of hemostats are provided with means for attaching and guiding the needle, whereby a single needle may be successfully employed with several hemostats after these have been clamped in position.

In the drawing:

Figure 1 is a perspective view of the hemostat portion of the surgical instrument of this invention, with the attachable surgical needle removed.

Figure 2 is a perspective view of the needle holder portion of the surgical instrument of this invention separated from the hemostat portion of Figure 1, including the needle.

Figure 3 is a side elevation of the surgical instrument shown in Figure 1, prior to the attachment of the surgical needle but after the tissue has been clamped.

Figure 4 is a side elevation similar to Figure 3 after the attachment of the surgical needle holder and needle but prior to its insertion in the tissue.

Figure 5 is a side elevation similar to Figures 3 and 4 but showing the surgical needle immediately after it has passed through the tissue and has grasped suture.

Figure 6 is a perspective view of the tip of the surgical instrument, omitting the tissue, and showing the position of the parts after the needle has drawn the suture upward through the tissue.

Figure 7 is a longitudinal section through the pivot axis of the surgical instrument taken along the line 7—7 in Figure 5 and showing the quick detachable arrangement for the surgical needle.

Figure 8 is a cross-section along the line 8—8 in Figure 7.

Figure 9 is a plan view, partly in horizontal section, taken along the line 9—9 in Figure 7.

Figure 10 is a perspective view of the tips of the clamping jaws of a modified form of the instrument wherein the tips are provided with end notches rather than apertures.

General arrangement

In general, the surgical instrument of this invention consists of a hemostat or surgical clamp combined with a quickly attachable and detachable surgical needle holder including a surgical needle. The hemostat consists of a pair of clamping jaws pivoted around a pivot pin, and having means for guiding a suture along one of the jaws and through an aperture or notch tip thereof.

The pivot pin of the instrument is extended laterally to provide a pivot for the needle holder, the latter being offset so that the needle will pass through the apertures in the tips of the clamping jaws. A quick detachable connection is provided

whereby the needle holder may be instantly attached to or detached from the clamping pivot pin, so that the tissue may first be clamped and the bleeding stopped before the needle is attached and used. Hitherto in surgical operations it has been necessary to attach hemostats to the tissue which has been cut, so that bleeding will be stopped. In order to make this stoppage permanent, it has been necessary to pass surgical sutures through the tissue and to tie the sutures after they have been passed through the tissue.

It has required exceedingly accurate work on the part of the surgeon to insert the needle at the proper point after the hemostat has been clamped upon the tissue. The use of the surgical needle has demanded skill and concentration on the part of the surgeon.

Moreover, the difficulty has always been present where bleeding and darkness caused the needle to be inaccurately inserted, so that the suture did not properly halt the flow of blood. This occurs frequently in operations in internal cavities of the body, such as throat operations. Under such circumstances the inaccessibility of the tissue makes accurate insertion of the needle a somewhat difficult task particularly if it is complicated by the presence of bleeding for it conceals the tissue.

In the present invention, however, if the bleeding continues after the jaws of the instrument have been clamped, the instrument may be unclamped and the jaws reclamped in another position. This may be repeated until it is found that the bleeding stops. The surgical needle holder and needle are then instantly attached, and the needle is automatically guided into position to pass through the tissue and pick up the suture, without any attention on the part of the operator other than to apply pressure to the handle of the needle holder. When the suture has been withdrawn, the needle holder may instantly be detached and the suture tied. Furthermore, the same needle holder and needle may be used in connection with several hemostats, such as where an abdominal operation is being conducted.

Hemostat portion construction

Referring to the drawing in detail, Figure 4 shows the surgical instrument of this invention as consisting of a hemostat portion, generally designated 10, and a needle holder, generally designated 11. The hemostat portion 10 of the instrument consists of a pair of clamping arms 12 and 13 (Fig. 1), pivoted around a pivot pin 14 (Fig. 7) and having a pair of clamping jaws 15 and 16 respectively provided with apertures 17 and 18 in the tips thereof. At their opposite ends the arms 12 and 13 are provided with finger loops 19 and 20, adjacent which are inter-engaging locking portions 21 and 22. The locking portion 21 is provided with a plurality of teeth 23 of ratchet form engageable by a pawl-like tooth 24 upon the locking portion 22.

The arm 13 adjacent the pivot pin 14 is provided with a transverse aperture 25 between the spaced portions 26 of the arm 13. The arm 12 is provided with a portion 27 of reduced width adapted to pass through the aperture 25.

The pivot pin 14 passes through aligned apertures 28, 29 and 30 in the arm portions 26 and 27 respectively (Fig. 7). The aperture 28 is provided with a flared portion 31 to receive the end 32 of the pivot pin 14 which has been upset or enlarged to prevent withdrawal of the pivot pin 14. The flared portion 32 of the pivot pin 14 is formed upon a reduced diameter portion 33 at the end thereof (Fig. 7).

Surrounding the pivot pin 14 is a suture guide 34 having a central aperture 35 through which the pivot pin 14 passes, and a peripheral groove 36 adapted to serve as a guide for a surgical suture 37. The opposite ends of the suture 37 are held by clamps 38, 39 and 40, mounted on the arm 13 (Fig. 1). The mid-portion of the suture passes through apertures 41 in the side

walls of the clamping jaw 16 adjacent the aperture 18, so that the suture passes across the aperture 18. The suture guide 36 is provided for the purpose of conducting the suture 37 around the needle holder 11 and to prevent interference of the one with the other.

Beyond the suture guide disc 34 the pivot pin 14 is provided with an enlarged portion 42 having a pair of flat spots 43 on the periphery thereof (Figs. 7 and 8). The outer end of the pivot pin 14 is tapered to a conical shape (Fig. 7) as at 44, so as to facilitate the attachment of the needle holder 11. The arms 12 and 13 are provided with angled or inclined portions 45 and 46 adjacent the pivot pin 14 serving as stops for limiting the clamping movement of the clamping jaws 15 and 16 (Figs. 8 and 9).

Needle holder construction

20 The needle holder 11 (Fig. 2) includes an arm 50 having a bent portion 51 terminating in a transverse portion 52. The latter is provided at its mid-portion with an aperture 53 and continues on the opposite side thereof in a bent portion 54 continuing beyond the bend in a needle-holding arm 55.

25 The needle-holding arm 55 is provided with a longitudinal bore 56 (Fig. 4) forming a socket for a surgical needle 57 and having a boss 58 with a threading aperture 59 receiving a set screw 60 for holding the needle 57 in the bore 56. The needle 57 is provided with an arcuately bent portion 61 having a needle point 62 and a transverse suture slot 63 adjacent the point 62. The slot 63 is provided with a pair of prongs 64 for preventing the suture from slipping accidentally out of the slot. The prongs 64 are separated by a gap, however, so that the needle may be removed from the suture (Fig. 6) after the latter has been drawn through the tissue 65. At its 30 opposite ends the needle holder 11 is provided with a flat spring 66 secured as at 67 to the arm 50 (Fig. 2). The arm 50 terminates in a handle 68 arranged for convenient grasp by the surgeon.

35 Mounted on the enlarged portion 42 of the pivot pin 14 (Figs. 7 and 9) is a sleeve 69 having a hub 70 with an annular groove 71 mating loosely with the aperture 53 in the needle holder 11. The sleeve 69 is provided with a knurled thumb nut portion 72 connected to the hub 69 by a neck 73 (Figs. 8 and 9). The neck 73 is cut away at 74 on its upper and lower surfaces so as to be of slightly less thickness than the diameter of the pivot pin 14 between the flat spots 43. Secured as at 75 to the neck 73 is a U-shaped double spring 76 the arms 77 of which are adapted to engage the flat spots 43 within the notches 78 formed by these flat spots 43. By this means the needle holder 11 is quickly attached or detached from the hemostat portion 10, as hereinafter described.

40 The hub 70 of the sleeve 69 on the side opposite the notches 78 is seated in a circular recess 79 (Fig. 7) formed in the suture guide disc 34. The sleeve 69 is provided with a bore 80 fitting snugly but slideably over the enlarged portion 42 of the pivot pin 41.

Modified hemostat jaw construction

45 The modified hemostat jaw construction shown in Figure 10 is generally similar to the hemostat portion 10 shown in Figures 1 to 5 inclusive. In the modified construction, however, the clamping jaws 15 and 16 are provided with upper and lower notches 81 and 82 instead of the apertures

17 and 18 shown in the principal form of the invention. The notches 81 and 82 are open toward the front of the hemostat portion 10, so that after the suture 37 has been drawn through the tissue in the manner analogous to that shown in Figure 6, the hemostat portion 10 may be drawn toward the surgeon and the upper portion of the suture 37 will merely slip out through the gap between the side portions 83 of the upper jaw 15 adjacent the upper notch 81. The suture 37, however, passes through slots 84 in the side portions 85 of the clamping jaw 16 adjacent the notch 82. This may be done without previously detaching the needle 61 from the suture 37, as is necessary in the principal form of the invention shown in Figure 6.

Use of the instrument

In the use of the invention let it be assumed that the suture 37 has been threaded through the apertures 41 or 84 in the clamping jaws 15 and 16, that the portions thereof entering and leaving the instrument are held by the clips 38, 39 and 40, (Fig. 1). The suture 37 at its mid-portion on one side is threaded through the groove 36 in the suture guide disc 34.

The surgeon now performs the operation, such as the removal of a tonsil indicated by the tissue 65, of which a portion has been removed, leaving a raw end 85 from which bleeding is taking place. The surgeon grasps the hemostat portion 10 and quickly inserts the clamping jaws 15 and 16 on opposite sides of the tissue 65, bringing them into clamping engagement therewith over the blood vessels and holding them in clamping engagement by means of the interlocking of the clamping portions 21 and 22 adjacent the finger loops 19 and 20. If the bleeding does not cease by reason of this clamping action, the clamping jaws 15 and 16 may be unclamped, shifted to another portion of the tissue 65 and reclamped.

When the bleeding has subsided, the surgeon removes the blood either by swabs or by a vacuum device, whereupon the tissue is ready to be sutured in order to tie the walls of the blood vessels tightly together and permanently prevent bleeding.

The surgeon now grasps the needle holder 11 and slips the bore 80 over the pivot pin 14. As the spring arms 77 of the spring 76 pass over the surface of the pivot pin 14 they snap into the notches 78 formed by the flat spots 43 (Figs. 7 and 8) temporarily locking the needle holder 11 in position upon the pivot pin 14. If necessary, the thumb nut 72 is twirled between the fingers until the parts are in the position of Figure 8 whereby the sides 74 of the neck 73 are substantially parallel to the flat spots 43 upon the pivot pin 14. The parts are now in the position shown in Figure 4.

The surgeon now grasps the handle 68 and pulls it toward the arm 12 (Fig. 5) thereby forcing the tip 62 of the needle portion 61 downward through the tissue 65 and causing the suture 37 to snap into the needle slot 63. The handle 68 is now released, whereupon the spring 66 urges the handle 68 away from the arm 12 (Figs. 4 and 5) causing the needle portion 61 to be drawn back through the tissue 65, bringing with it a loop of the suture 37 (Fig. 6).

The suture 37 is now removed from the needle slot 63 and the needle holder 11 removed from the pivot pin 14. This is accomplished by turning the thumb nut 72 and sleeve 69 through a right angle from the position shown in Figures

7, 8 and 9. When this is done, the neck portions 73 move beneath the spring arms 77, forcing them apart to a distance greater than the separation of the flat spots 43. The sleeve 69, and the remainder of the needle holder mounted thereon, can now be withdrawn from the pivot pin 14. The suture can now be tied and the hemostat portion 10 unclamped and withdrawn.

10 When a large incision is made in certain types of surgical operations, such as abdominal operations, a large number of hemostats are frequently employed. Ordinarily in such instances, it is necessary to insert a separate needle adjacent each hemostat and tie the sutures one by one. With the use of the present instrument, however, one needle holder 11 may be employed successively with a number of hemostat portions 10 and the sutures can be quickly and accurately 15 inserted one after another, without the necessity of careful thought on the part of the surgeon. Thus the instrument of the present invention accomplishes the insertion of the sutures almost automatically with a minimum of thought on the part of the surgeon. The surgeon's mind is, therefore, freed from the care 20 ordinarily needed in inserting the sutures, and consequently is able to concentrate on other matters arising during the operation. This advantage is particularly important where an incision 25 unexpectedly discloses pathological conditions the existence of which was not previously known or only slightly suspected. Under these circumstances the surgeon is able to deal with the 30 newly discovered conditions and to perform the additional surgery immediately without losing any time guiding the suture needles into place.

While a specific embodiment of the invention has been described and illustrated, it will be 35 understood that various modifications may be made within the scope of the appended claims without departing from the spirit of the invention.

What I claim is:

- 45 1. In a surgical instrument, a hemostat device having pivoted clamping portions engageable with the tissue to be sutured, an attachable and detachable surgical needle holder connectable to the pivot of said device, and a surgical needle arranged to be mounted in said holder, said hemostat device having a notch in one end of at least one of said clamping portions to receive the suture thread and thereby locate the thread in the path of the needle.
- 50 2. In a surgical instrument, a hemostat device having clamping portions engageable with the tissue to be sutured, an attachable and detachable surgical needle holder connectable to said device, a surgical needle arranged to be mounted in said holder, said hemostat device having a notch in one end of at least one of said clamping portions, and means for holding a suture therein and extending across said notch in the path of said needle.
- 55 3. In a surgical instrument, a hemostat device having pivoted clamping portions engageable with the tissue to be sutured, an attachable and detachable surgical needle holder connectable to said device at the pivot thereof, and a surgical needle arranged to be mounted in said holder, said needle being arcuately curved at its forward portion, and having a transverse suture slot therein for receiving the suture.
- 60 4. In a surgical instrument, a hemostat device having clamping portions engageable with the

tissue to be sutured, an attachable and detachable surgical needle holder connectable to said device, and a surgical needle arranged to be mounted in said holder, said needle being arcuately curved at its forward portion, and having a slot with prongs at the edges thereof for receiving the suture and for preventing the accidental dislodgement thereof.

5. In a surgical instrument, a hemostat device having a pivot pin projecting from one side thereof and provided with indentations and a pair of clamping arms pivotal around said pivot pin, a surgical needle holder detachably mounted on said pivot pin, a surgical needle secured to said needle holder, and means carried by said needle holder engaging within said indentations for selectively locking said needle holder to said pivot member.

6. In a surgical instrument, a hemostat device having a pivot member and a pair of clamping arms pivotal around said pivot member, said pivot member projecting beyond the clamping arms and having indentations in the free end thereof for holding the suture, one of said arms having a notch, a surgical needle holder detachably mounted on said pivot member, a surgical needle secured to said needle holder having a slot for engaging the suture and looping the same, and manually releasable detent carried by the surgical needle holder for being received in said indentations for detachably connecting said needle holder to said hemostat device.

7. In a surgical instrument, a hemostat device having a pivot member and a pair of clamping arms pivotal around said pivot member, means for holding a suture in engagement with one of said arms, a surgical needle holder detachably and pivotally mounted on said pivot member, a surgical needle secured to said needle holder,

said pivot member having a notch therein, and a detent carried by the needle holder releasably engageable with said notch.

8. In a surgical instrument, a hemostat device having a pivot member and a pair of clamping arms pivotal around said pivot member, means for holding a suture in engagement with one of said arms, a surgical needle holder detachably mounted on said pivot member, a surgical needle secured to said needle holder, said needle holder having a hub pivotally mounted on said pivot member and a detent carried by the hub of the needle holder responsive to the rotation of said hub for selectively locking and unlocking said needle holder relatively to said hemostat.

9. In a surgical instrument, a hemostat device having a pivot member and a pair of clamping arms pivotal around said pivot member, means for holding a suture in engagement with one of said arms, a surgical needle holder detachably mounted on said pivot member, a surgical needle secured to said needle holder, said needle holder having a hub pivotally mounted on said pivot member with a cut-away portion, said pivot member having a notch alignable with said cut-away portion, and resilient means engaging said notch for releasably locking said hub to said pivot member.

10. A needle holder for surgical instruments comprising a hub member attachable to a hemostat, a needle receiver pivotally mounted on said hub, and a latch yieldably mounted on said hub.

11. A needle holder for surgical instruments comprising a hub member attachable to a hemostat, a needle receiver pivotally mounted on said hub, and a latch yieldably mounted on said hub, said hub having a bore therethrough adapted to receive the pivot pin of a hemostat.

SIMON H. SAUTER.
